FOREIGN PATENT DOCUMENTS

CA 202390 * 4/2022
WO WO-D228397-001 * 4/2023Primary Examiner — George J Ulsh
Assistant Examiner — Christine Tucci(57) **CLAIM**

The ornamental design for a babies' nappy cover as shown and described.

DESCRIPTION

1. Babies' nappy cover

1.1 : Environmental View Front Fastening

1.2 : Environmental view Back Fastening

1.3 : Front view when fastened to the back

1.4 : Front view when fastened to the front

1.5 : Inside view

1.6 : Outside view

Newness and distinctiveness are claimed in the features of shape and/or configuration of the babies' nappy cover shown in the representations. The broken lines crossing claimed surfaces represent stitching and form part of the claim. The body shown as dashed lines does not form part of the claim. The rounded ends of the waistbands form no part of the claim.

1 Claim, 6 Drawing Sheets(56)
